COLOR TELEVISION RECEIVER WITH LARGE PROJECTION SCREEN

Georges Valensi, 3 Rue des Chaudronniers,
Geneva, Switzerland

Filed Oct. 14, 1959, Ser. No. 846,411

Claims priority, application France July 16, 1959

14 Claims. (Cl. 178—5.4)

This invention concerns a television system in which a carrier wave (modulated by a luminance signal l) carries the information for a detailed drawing of the scene to be shown at distance, whereas a subcarrier wave (modulated by a chrominance signal chr) carries the information for the colors of the various elements of said scene. It is well known that the human eye requires less color information than drawing information; therefore the chrominance spectrum occupies only a relatively small part of the frequency band occupied by the luminance spectrum; for example, the luminance occupies a band 4 megahertz wide, whereas the two side-bands of the color subcarrier (together with the subcarrier itself) occupy only a band 1 megahertz wide.

A satisfactory reproduction in colors of the scene scanned at a distant transmitting station can be produced by superimposing, upon a very detailed black and white drawing (on a projection screen), a relatively coarse colored picture, made of a relatively small number of "touches" having different colors. In order to secure the persistence of the impressions on the retina, the drawing with 625 scanning lines (in the European television standards) must be repeated 25 times per second; similarly, in the American television standards, the drawing, with 525 scanning lines, must be repeated 30 times per second; in both cases, the aspect ratio of the picture is 4/3. Assuming a band width of 400,000 hertz for one side-band of the modulated color subcarrier received at the receiving television station, the coarse colored picture mentioned above would contain only: in Europe

$$\frac{400,000}{25} = 16,000$$

distinct colored elements, and in United States of America:

$$\frac{400,000}{30} = 13,333$$

distinct colored elements. In Europe the coarse colored picture will have 110 lines of 146 distinct elements each; in U.S.A., it will have 100 lines of 133 distinct elements each.

In the American color television standard (National Television Standards Committee System, in brief "N.T.S.C. System"), the color subcarrier is both phase modulated and amplitude modulated; the phase gives the "hue," and the amplitude gives the "degree of saturation" of the color to be reproduced. Figure 2a shows in solid lines the luminance spectrum l , and in dotted lines the chrominance spectrum (chr); Figure 2b shows the circular diagram giving the phases for the various hues, with reference to the "color burst" sr (reference signal for color); the circle of Figure 2b is graduated in wavelengths λ_d expressed in millimicrons for the spectral colors, and in "complementary" wave-lengths λ_c for the purples. The description hereafter deals, in way of example only, with the application of the invention to the American N.T.S.C. system.

2

Figure 1 is a schematic representation of the color television receiving station in accordance with the invention; EP is the projection screen; in this case the received video-signal is assumed to have the spectrum shown on Figure 2a.

Two projectors (TC_1 , TC_2) of the Eidophor type are used simultaneously, each having a transparent plate (PL_1 , PL_2) rotating continuously around a vertical axis (A_1 , A_2), the upper faces of said plates being made electro-conductive by means of a very thin suitable transparent coating; the motions of said plates (PL_1 , PL_2) are perfectly synchronous, because the same electric motor (not shown on Figure 1) drives said plates by means of the same mechanism (Mec). A thin layer (P_1 , P_2) of a viscous oil having an appropriate electric conductivity is spread over the upper surface of each plate (PL_1 , PL_2). Transparent windows (f_1 , f_2) permit the illumination (through transparent plates PL_1 , PL_2) of said oil layers by means of powerful sources of white light (S_1 , S_2) located at the focus of concave mirrors and also at the focus of collimating lenses (LC_1 , LC_2), so that parallel luminous rays illuminate (at normal incidence) two homothetic rectangles (E_1 , E_2) of said oil layers (P_1 , P_2); these rectangles (E_1 , E_2) are scanned respectively by the pencils of the electrons produced by cathodes c_1 , c_2 —accelerated by anodes a_2 , a_2 —united into a cross-over inside aperture diaphragms d_1 , d_2 —concentrated on the oil layer by focussing magnetic coils sf_1 , sf_2 —horizontally deflected by coils h'_1 , h'_2 and by plates h_1 , h_2 —and vertically deflected by coils v_1 , v_2 .

The electroconductive faces of plates (PL_1 , PL_2) in contact with oil are raised to a high positive electric potential referred to cathodes (c_1 , c_2); the bombarding electrons produce (on rectangles E_1 , E_2) some "deformations" of the oil surface, due to the electrostatic forces developed by the electron spots; but these deformations disappear after a fraction of a second, because the oil is slightly electroconductive.

Rectangle E_2 (of oil layer P_2 , in tube TC_2) is imaged, through transparent window f'_2 , by objective lens LO_2 onto projection screen EP, in order to produce a detailed black and white drawing of the scene being scanned at the transmitting station; rectangle E_1 (of oil layer P_1 , in tube TC_1) is imaged, through transparent window f'_1 , by objective lens LO_1 , onto projection screen EP, in order to superimpose colored "touches" upon said drawing.

Like in a classical Eidophor projector for black and white television, two "bar systems" (B_1 , B_2) are associated with tube TC_2 , and lens LC_2 images bar system B_1 onto bar system B_2 , in such a manner that a luminous ray (such as r_1) going through, a part of rectangle E_2 without deformation is stopped by bar system B_2 , whereas a luminous ray (such as r_2) going through a part having a deformation goes freely through the slits of B_2 ; after objective lens LO , and after reflection on mirror M , said luminous ray r_2 contributes to the production (on screen EP) of the white image of the corresponding part of E_2 , the brightness of said image being proportional to the importance of the deformation of said part of E_2 . Therefore, in a classical manner, the desired black and white drawing is produced by Eidophor projector TC_2 on screen EP.

The object of the present invention is the creation (by means of tube TC_1) of the other "coarse colored image" of the scene being scanned at the transmitting station, in applying the principles illustrated by the appended Figures 3, 3a and 3b—or 3d and 3e, or 3f.

The diffraction of white light through the parts of the oil layer having a deformation producing (as explained hereafter) not only a white luminous point, but also colored spectra on both sides of said white point, it could

theoretically be possible to use the same Eidophor projector for producing the drawing (under the control of the luminance signal) and the color (under the control of the chrominance signal); but there would be a risk of interference between the respective actions of luminance signal l and chrominance signal (chr)—said interference producing either disturbing colored fringes, or undesirable color errors, on projection screen EP. The purpose of the present invention is to separate clearly the respective actions of luminance signal l and chrominance signal (chr).

The invention will be better understood in referring to the appended drawings, in which:

Figure 1a represents the left part and Figure 16 the right part of the color television receiving station in accordance with the present invention;

Figure 2a shows the spectrum of the received composite video-signal V in the N.T.S.C. System;

Figure 2b shows the circular diagram for the phase of the modulated color subcarrier in the N.T.S.C. System;

Figure 2c represents a phase detector;

Figure 2d represents the decoding electrode of the hue decoding cathode ray tube Td of Figure 1;

Figures 2e, 2f and 2g show a modification of part of Figure 1;

Figures 3, 3a, 3b, 3c, 3d, 3e and 3f illustrate the performance of projector TC_1 of Figure 1, producing the coarse colored picture of the scene being scanned at the transmitting station;

Figure 4 represents the color triangle divided in sectors corresponding to the various chromaticities that the human eye can discriminate easily from each other.

Figure 4a shows the saturation decoding cathode ray tube Td' and the hue decoding cathode ray tube Td , in case of a color television system based on the color triangle of Figure 4;

Figure 1c shows a single Eidophor projector TC , replacing the two Eidophor projectors (TC_1, TC_2) of Figure 1; and Figure 1d shows parts of said single projector TC of Figure 1a. Figure 1 represents schematically the invention as applied to the American N.T.S.C. color television system.

Figure 3 shows the source of white light S_1 of Figure 1, as well as the collimating lens LC_1 and the plate PL_1 of tube TC_1 with its oil layer P_1 . $R_1, R_2, R_3 \dots$ represent elemental light diffracting gratings produced by the electrons (issued from cathode c_1) on part E_1 of oil layer P_1 , said gratings having respectively $n_1, n_2, n_3 \dots$ parallel rippled lines per millimeter; these lines (perpendicular to the plane of Figure 3) are the so called "deformation" of the oil surface due to the pressure distribution corresponding to the discrete linewise electrical charges distribution produced by the electron pencil which is horizontally deflected not only by magnetic coil h'_1 (energized by a sawtooth wave at the scanning lines frequency), but also by plates h_1 energized by a frequency modulated sine-wave as explained hereafter. In the absence of said sine-wave, a uniform distribution of electrons would be produced on the oil surface during the linear part of the sawtooth waveform applied to coil h'_1 , and said oil surface would remain smooth; if, on the contrary, said frequency modulated sine wave is applied to plates h_1 , the size of the electron spot varies from point to point on the oil surface, and a deformation, in form of an elemental diffracting grating R_1 , is produced.

RL (Figure 3) is a network of small elemental lenses (l_1, l_2, l_3) having all the same focal length f , and corresponding to diffracting gratings R_1, R_2, R_3 . The focal points of all these elemental lenses are on the same plane F which contains a mask M constituted by opaque parts (m, m') separated from each other by transparent parts (e); although mask M is exactly on focal plane F, it is

represented on Figure 3a slightly before plane F (along the light path), in order to clarify the explanation hereafter.

If mask M did not exist, each elemental diffracting grating R_1 would produce (on plane F) a white image I_1 of light source S_1 , and also two first order normal spectra (s_1 and s'_1) symmetrically located on both sides of said image I_1 . In said spectra (s_1 or s'_1) the distance d between central image I_1 and the colored line corresponding to wave-length λ is given by the known formula:

$$d=f.\lambda.n_1$$

n_1 being the number of parallel lines of grating R_1 by unit length, because s_1 (or s'_1) is a first order spectrum, and because source S_1 illuminates oil layer P_1 at normal incidence.

Figure 3a shows, for example, the luminous groups ($s_1I_1s'_1$), ($s_2I_2s'_2$), ($s_3I_3s'_3$) corresponding to elemental diffracting gratings R_1, R_2, R_3 of Figure 3. The opaque bands m and m' (of mask M) cut off the central images $I_1, I_2, I_3 \dots$ as well as a great part of spectra $s_1, s'_1, s_2, s'_2, s_3, s'_3 \dots$ Therefore the only monochromatic luminous radiations produced by the diffracting gratings which can go through transparent parts e (of mask M) and reach the projection screen EP through objective LO_1 (Figure 1) are those having wave-lengths comprised in an interval $\Delta\lambda$ given by the formula:

$$e=\Delta d=f.n_1.\Delta\lambda$$

30 n_1 being the number of lines of grating R_1 per millimeter, if $f, \Delta d$ and $\Delta\lambda$ are also expressed in millimeters.

It is desired that $\Delta\lambda$ corresponds to nearly one third of the normal visible spectrum, which extends from red light ($\lambda_r=7.10^{-4}$ mm.) to violet-blue light ($\lambda_b=4.10^{-4}$ mm.).

35 Therefore the order of magnitude of the width e of a transparent part of mask M (Figure 3a) should be:

$$e=f.n_1.\frac{7-4}{3}.10^{-4} \text{ mm.}$$

40 The Eidophor television projectors commonly used for black and white television have a hair-pin cathode producing an electron beam of 20 microamperes under an accelerating voltage of 20 kilovolts, and the associated electron optics produces, on the oil layer, an electron spot 0.02 millimeter wide and 0.1 millimeter long, said spot being one "line" of an elemental diffracting grating. It is desired that the distance between two such lines equals at least twice the width of a line, so that the maximum number of lines per millimeter is 16.

45 Figure 3b shows with more details one elemental diffracting grating R_1 of oil layer P_1 , and the corresponding elemental lens l_1 within the network of lenses RL of Figure 3. It is necessary that the two first order spectra (s_1, s'_1) produced by diffracting grating R_1 reach (entirely) the corresponding elemental lens l_1 .

50 As explained hereafter, the electron beam emitted by cathode c_1 of tube TC_1 (Figure 1) produces, on successive horizontal scanning lines of rectangle E_1 of oil layer P_1 , within the same elemental square of E_1 below lens l_1 , different diffracting gratings (R_b, R_v, R_r), having appropriate numbers of lines per millimeter (n_b, n_v, n_r) for producing (through the transparent parts e of mask M) blue, green and red lights respectively; as explained hereafter, $n_b > n_v > n_r$. The maximum diffraction angle ($\alpha_{\max}$) 55 corresponds to the red radiations (wave length

$$\lambda_r=0.7.10^{-3}$$

millimeter) diffracted by the most diffracting grating R_b . If l_1 is the width of elemental lens l_1 (Figure 3b), d the distance (in millimeters) between oil layers P_1 of tube TC_1 and network RL of elemental lenses, the following condition must be fulfilled for the first order spectra:

$$\sin \alpha_{\max}=n_b \lambda_r$$

$$l_1=2d \cdot \tan \alpha_{\max}=2d \cdot n_b \cdot \lambda_r$$

because angle $\alpha_{\max}$ being small, its tangent is equal to its sinus.

It is desired that blue light goes through mask M in front of a grating R_b —green light, in front of a grating R_v —and red light, in front of a grating R_r .

f being the focal length of all elemental lenses of network RL, and δ being the width of an opaque part (m) of mask M, the following equations must apply:

$$\frac{\delta}{2} = f \cdot \lambda_b \cdot n_b = f \cdot \lambda_v \cdot n_v = f \cdot \lambda_r \cdot n_r$$

As $\lambda_b = 0.4 \cdot 10^{-3}$ mm. (blue light), $\lambda_v = 0.5 \cdot 10^{-3}$ mm. (green light, and $\lambda_r = 0.7 \cdot 10^{-3}$ mm. (red light),

$$n_v = \frac{n_b \cdot 4}{5} \quad n_r = \frac{n_b \cdot 4}{7}$$

For example, if $n_b = 16$, $n_v = 12.8$ and $n_r = 9.14$. If $n_b = 8$, $n_v = 6.4$ and $n_r = 4.57$. The distance between P_1 and RL (Figure 3b) is, in both cases determined by the above formula

$$d = \frac{l_1}{2n_b \cdot \lambda_r}$$

when l_1 and n_b are known.

The focal length f of elemental lenses l_1 of network RL and the dimensions of the various parts (m , m' , e) of mask M (Figures 3a and 3b) must be such that objective lens LO_1 (represented by a single horizontal line on Figure 3b, and having a diameter of 0 millimeter) receives only the lights of desired colors, but also receives the colored lights of one third (blue, green or red) of each first order spectrum diffracted by the various elemental squares of rectangle E_1 of oil layer P_1 (Figure 1).

As the red radiations must (at most) reach the right end of the considered element (m' , e , m , e , m') of mask M, and as this element has a width

$$l = 2 \left(\frac{\delta}{2} + e + e \right)$$

δ being the width of an opaque part m , whereas $\delta' = 2e$ is the width of an opaque part m' , the following condition must be satisfied:

$$l = 2 \left(\frac{\delta}{2} + e + e \right) = \delta + 4e = 2 \cdot f \cdot n_r \cdot \lambda_r$$

Objective lens LO_1 must cover the 13,300 elemental squares of rectangle E_1 of oil layer P_1 (100 lines of 133 elemental squares each) in the case of the American N.T.S.C. color television system; therefore the width of mask M must be 133 l , and its height must be 100 l .

Consequently:

$$O = l \sqrt{133^2 + 100^2} = l \sqrt{27,689} = 167l$$

If, for example, $O = 250$ millimeters, then:

$$l = \frac{250}{167} = 1.49 \text{ millimeters}$$

and

$$f = \frac{l}{2 \cdot n_r \cdot \lambda_r} = \frac{1.49 \times 10,000}{2 \times 8 \times 7} = 133 \text{ millimeters}$$

in the case (mentioned above) where $n_r = 8$, $n_v = 6.4$, $n_b = 4.57$.

Therefore:

$$\begin{cases} \delta = 2f \cdot \lambda_r \cdot n_r = 2 \times 133 \times 32.10^{-4} = 0.85 \text{ mm.} \\ e = \frac{l - \delta}{4} = \frac{1.49 - 0.85}{4} = 0.16 \text{ mm.} \\ \delta' = 2e = 0.32 \text{ mm.} \end{cases}$$

The mask M (the dimensions of which are so determined) can be made by photographing a much enlarged black and white drawing, upon a thin grains photographic film. The width l_1 of an elemental lens l_1 of network

RL must be equal to the width l of one element of mask M; therefore $l_1 = 1.49$ millimeter.

Rectangle E_1 of oil layer P_1 must have the same dimensions as mask M; therefore its width is

5 $E = 133l = 133 \times 1.49 = 198 \text{ millimeters}$

Objective lens LO_1 , in association with the elemental lens l_1 of network RL, produces, on projection screen EP (Figure 1) a coarse colored picture of the scene being scanned at the distant transmitting station; if said picture has a width of C meters, and if projection screen EP is at a distance of D meters from objective lens LO_1 (which images rectangle E_1 onto screen EP), the magnification produced by this optical system is:

15 $g = \frac{C}{E}$

and the focal length of lens LO_1 must be:

20 $F = \frac{D}{g}$

If, for example $C = 6$ meters, $D = 15$ meters, as $E = 0.198$ meter,

25 $g = \frac{600}{19.8} = 30$

and

30 $F = \frac{15}{30} = 0.50 \text{ meter}$

The distance between LO_1 and oil layer P_1 is of the order of 60 centimeters. The optical system, constituted by the elemental lenses of network RL and by objective lens LO_1 , must be well corrected for achromaticity and 35 for the field; but the conditions to be imposed for the other aberrations are much less stringent, because the colored picture to be produced on the projection screen is relatively coarse. For example 4 points of the black and white drawing produced by tube TC_2 (Figure 1) correspond to the same "colored touch" (or element) of said coarse colored picture; therefore the registration of said colored picture upon said drawing does not raise any difficult optical problem for mirrors M_1 and M_2 of Figure 1; moreover, some correction can be made electrically in 40 scanning the two homothetic rectangles E_1 and E_2 (in synchronism) within tubes TC_1 and TC_2 , respectively.

The prototype of lens network RL (Figure 3) is obtained in the following manner. A number of cubic elements (having 1.5 millimeter sides) are cut into a glass 50 plate having parallel faces; these cubic elements are juxtaposed on a sphere having an appropriate radius of curvature, and they are simultaneously all shaped and polished. Then these elemental lenses are juxtaposed on a plate covered with an appropriate paste which is later polymerised by heating, in order to obtain a solid block, which 55 is precisely the desired prototype. With this prototype as a mould, a number of lens-networks such as RL (Figure 3) can be obtained (cheaply), in Plexiglas (methacrylate of methyl).

60 Figure 3d shows a modification of the optical system of Figures 1 and 3. In this case, mask M is juxtaposed to network RL of elemental lenses, as Figure 3e shows it in a more detailed manner. Also a bar system M' is used, having opaque parts (b wide), separated by slits 65 (a wide); finally, use is also made of a screen E (provided with relatively narrow holes), located in the focal plane of the elemental lenses of network RL. The purpose of using bar system M' and screen E is: to secure a good parallelism of the white light rays illuminating (at 70 normal incidence) the various elements of rectangle E_1 of oil layer P_1 , and to cut off any stray light, other than the colored lights which it is desired to throw on projection screen EP.

On Figure 3d, S_1 is a powerful source of white light 75 (for example, an electric arc in pressurized xenon),

located at the center of a small spherical mirror m_s , which images said electric arc onto itself. S'_1 is the image of S_1 through lens L , within the hole of diaphragm d . S'_1 is located at the focus of collimating lens LC_1 which illuminates (at normal incidence) rectangle E_1 of oil layer P_1 , through transparent plate PL_1 of tube TC_1 (Figure 1). The electrons emitted by cathode C_1 of tube TC_1 create elemental diffracting gratings (such as R_1 , R_2 , above slits a of M' , Figure 3e). l_1 , l_2 are the elemental lenses of network RL corresponding respectively to said gratings R_1 , R_2 . The opaque parts (m , m') of mask M (separated by transparent parts e of said mask) cover the bases of said elemental lenses l_1 , l_2 as shown on Figure 3e. As the center of each opaque part m of M is just above each slit a of M' , the non-diffracted white light is cut off by said part m , whereas the colored light (diffracted by grating R_1 for example) goes through the transparent parts e , both sides of m ; therefore, at the focus of elemental lens l_1 , are produced two small colored images (S''_1 and S'''_1) of light source S_1 , very close to each other, inside a hole of screen E . Objective lens LO_1 (which in association with the elemental lenses of RL and with mirror M_1 , images rectangle E_1 of oil layer P_1 onto projection screen EP) produces colored touches corresponding respectively to said elemental lenses, in such a manner that said touches build a coarse colored picture of the scene being scanned at the distant transmitting station.

An elemental diffracting grating R_1 (having n_1 lines per millimeter) diffracts the blue light ($\lambda_b=0.4 \cdot 10^{-3}$ mm.) of an angle α_b , and diffracts the red light ($\lambda_r=0.7 \cdot 10^{-3}$ mm.) of an angle α_r :

$$\sin \alpha_b = n_1 \cdot \lambda_b \quad \sin \alpha_r = n_1 \cdot \lambda_r$$

These angles (α_b , α_r) are small enough for having a tangent equal to the sinus.

If D designates (in millimeters) the distance between oil layer P_1 and the juxtaposed mask M and network of lenses RL , the (normal) first order spectrum occupies (on mask M) the space limited by points distant respectively of d_b and d_r from the middle of opaque part m (or from the middle of the base of the corresponding elemental lens l_1), with:

$$d_b = D \tan \alpha_b = D n_1 \cdot \lambda_b \quad (\text{which corresponds to blue})$$

$$d_r = D \tan \alpha_r = D n_1 \cdot \lambda_r \quad (\text{which corresponds to red})$$

The transparent part (e) between two opaque parts (m , m') must correspond to one third of said normal first order spectrum; therefore:

$$e = D \cdot n_1 \cdot \frac{\lambda_r - \lambda_b}{3} = D \cdot n_1 \cdot 10^{-4} \text{ millimeter}$$

In order to have, on projection screen EP , colors as much saturated as it is economically possible, n_1 should be the smallest of the numbers n_b , n_v , n_r , therefore n_1 should be made equal to 4.57. Therefore:

$$e = D \times 4.57 \times 10^{-4} \text{ millimeters} \quad (1)$$

The opaque part m of mask M must have a width δ such that the following condition is satisfied:

$$\frac{\delta}{2} = D \cdot n_1 \cdot \lambda_f = D \cdot n_v \cdot \lambda_v = D \cdot n_r \cdot \lambda_r$$

or $\delta = 2D \cdot 32 \cdot 10^{-4}$ (2)

The objective-lens LO_1 (having a diameter O millimeters) must cover all the elements of mask M , the width of one element being:

$$l = \frac{\delta'}{2} + 2e + \delta = \delta + \delta' + 2e$$

δ' being the width of an opaque part m' of mask M . Therefore:

$$\frac{O}{167} = \delta + \delta' + 2e$$

If $O=250$ millimeters, this becomes:

$$\delta + \delta' + 2e = 1.49 \text{ mm.} \quad (3)$$

The red radiation ($\lambda_r=7.10^{-4}$ mm.), when diffracted by the most diffringent grating R_f ($n_f=8$ lines per millimeter), should not go further than the end of the corresponding opaque part m' of mask M . The limiting condition is therefore:

$$\frac{\delta}{2} + e + \delta' = D \cdot n_f \cdot \lambda_r$$

or

$$\frac{\delta}{2} + e + \delta' = D \cdot 8 \cdot 7 \cdot 10^{-4} = D \cdot 56 \cdot 10^{-4} \text{ mm.} \quad (4)$$

If Equation 4 is subtracted from Equation 3, and if account is taken of Equation 2, the following equation is obtained:

$$D = \frac{14900}{32 + 4.57 + 56} = 163 \text{ millimeters}$$

Therefore: $\delta = 2 \times 163 \cdot 32 \cdot 10^{-4} = 1.04 \text{ millimeters}$
 $e = 163 \times 4.57 \cdot 10^{-4} = 0.074 \text{ millimeter}$
 $\delta' = l - \delta - 2e = 1.49 - 1.04 - 0.148 = 0.302 \text{ mm.}$

Again, the width of rectangle E_1 of oil layer P_1 of tube TC_1 (Figure 1) is $133 \cdot l = 198$ millimeters, each elemental square of said rectangle E_1 having sides of 1.5 millimeter.

In case of Figure 3d, the system made of network RL of elemental lenses and mask M can be realized in the following manner: in a rigid frame are assembled 133 strips (moulded in "Plexiglas," metachrylate of methyle) having each 100 elemental lenses 1.5 millimeter wide; this assembly is settled upon a mask M obtained by photographing a much enlarged black and white drawing on a thin grains photographic plate.

In the case of Figures 3d and 3e, the focal length of objective lens LO_1 can be 0.80 meter, said lens LO_1 being at $D=25$ meters of a projection screen $G=6$ meters wide; the magnification produced by said objective lens being

$$\frac{25}{0.80} = 30$$

the distance between network RL of elemental lenses and screen E can be of the order of 50 millimeters.

Figure 3f shows another modification of the optical system associated with tube TC_1 of Figure 1. In this case, no network of elemental lenses (such as RL , Figure 1) is used; but use is made of two bar systems M , M' , conjugated with each other in such a manner that the slits (a) of M' are in front of the opaque parts (m) of M , whereas the opaque parts b of M' are in front of the transparent parts (e) of M . A powerful source of white light S_1 (not shown on Figure 3f) illuminates, at normal incidence, the oil layer P_1 on which the electrons, emitted by cathode C_1 of tube TC_1 (Figure 1), create elemental diffracting gratings R_1 on each elemental square of a rectangle E_1 of said oil layer P_1 . For example, R_1 (Figure 3f) corresponds to 3 gratings (R_b , R_v , R_r) juxtaposed on parallel lines in a plane (P_1) perpendicular to the plane of Figure 3f, said gratings having respectively n_b , n_v , n_r lines per millimeter.

Lens objective LO_1 (represented as a single horizontal line on Figure 3f) images said rectangle E_1 onto projection screen EP , after reflection on mirror M_1 (Figure 1), and objective LO_1 covers entirely the 100 lines of 133 elements of mask M .

Each diffracting grating (R_1) produces, at a distance D millimeters from oil layer (P_1) a central white image of source S_1 , and, on both sides of said image, various diffraction spectra. The first order spectra are well separated from each other and quite distinct; the spectra of 2nd, 3rd orders overlap each other and are much less bright, so that they produce (on projection screen EP) only a small diffuse white light; account should be taken

of that in the adjustment of rheostat r , r' associated with pentode L (luminance weighting device) shown on Figure 1, as explained hereafter.

In the first order diffraction spectra, the red radiations are the most distant from the middle of opaque part m of mask M in front of diffracting grating R_i ; this distance of the red radiation has the following values in case of gratings R_b , R_v , R_r respectively:

$$\begin{aligned} d_b &= D \cdot n_b \cdot \lambda_r \\ d_v &= D \cdot n_v \cdot \lambda_r \\ d_r &= D \cdot n_r \cdot \lambda_r \end{aligned}$$

($n_b > n_v > n_r$), d_b , d_v , d_r and D being expressed in millimeters and $\lambda_r = 0.7 \cdot 10^{-3}$ millimeter.

If δ is the width of an opaque part m of mask M, and if e is the width of a transparent part e of said mask M, an element of M has a width:

$$l = \frac{e}{2} + \delta + \frac{e}{2} = \delta + e$$

As objective lens LO_1 (having a diameter of O millimeters) must cover all the elements of mask M (100 lines of 133 elements),

$$l = \delta + e = \frac{O}{167}$$

The greatest number of lines per millimeter of gratings R_i (as mentioned above) is $n_b = 16$ lines per millimeter. It is necessary that the "blue" third of first order spectrum goes alone through transparent part e of mask M in case of a diffracting grating R_b —that the "green" third alone goes through (e) in case of a diffracting grating R_v —and that the "red" third alone goes through (e) in case of a diffracting grating R_r . Therefore:

$$\frac{\delta}{2} = D \cdot n_b \cdot \lambda_f = D \cdot n_v \cdot \lambda_v = D \cdot n_r \cdot \lambda_r$$

Two cases can be considered:

1st case:

$$n_b = 16 \quad n_v = 16 \times \frac{4}{5} = 12.8 \quad n_r = 16 \times \frac{4}{7} = 9.14$$

$$2nd case: n_b = 8 \quad n_v = 6.4 \quad n_r = 4.57$$

In order to obtain saturated colors on projection screen EP (Figure 1), the width e of a transparent part (e) of mask M should be equal to the third of the width of the first order spectrum diffracted by the least diffracting grating; therefore:

$$e = D \cdot n_r \cdot \frac{7-4}{3} \cdot 10^{-4} = D \cdot n_r \cdot 10^{-4} \text{ millimeter}$$

For determining D, δ , and e , the three above equations must be used:

$$\delta + e = \frac{O}{167}$$

$$\frac{\delta}{2} = D \cdot n_r \cdot \lambda_r$$

$$e = D \cdot n_r \cdot 10^{-4} \text{ mm.}$$

In the first case ($n_b = 16$; $n_v = 12.8$; $n_r = 9.14$), with $O = 250$ mm., the following values are obtained:

$$\begin{aligned} D &= \frac{1.49 \times 10,000}{2 \times 16 \times 4 + 9.14} = 108 \text{ millimeters} \\ \delta &= 2 \times 108 \times 16 \times 4 \cdot 10^{-4} = 1.38 \text{ millimeters} \\ e &= 108 \times 9.14 \cdot 10^{-4} = 0.0987 = 0.1 \text{ millimeter} \end{aligned}$$

In the second case: $D = 217$ mm., $\delta = 1.39$ mm.,

$$e = 0.099 = 0.1 \text{ mm.}$$

Some care must be taken for focusing, in an appropriate manner, the electrons on the oil layer during all the scanning of said layer by the electron pencil. Figure 3c shows the rectangle E_1 of oil layer P_1 of tube TC_1 of Figure 1, and shows also a horizontal segment marked

(RL, M) having the same width as rectangle E_1 ; this segment is the network RL of elemental lenses in case of Figure 3b, or Figure 3d, and is the mask M in case of Figure 3f. (RL, M) is, in any case, an obstacle for the electron pencil, so that the angle between the electron pencil scanning rectangle E_1 and the oil layer must be less than 50 degrees (see hereafter). aa' (Figure 3c) represents one horizontal scanning line, c_1 the cathode of tube TC_1 , a_1 the anode, d_1 the diaphragm (cross-over),

10 h_1 the auxiliary horizontally deflecting plates energized by the frequency modulated wave $A_1 \cdot \sin w_1 t$, s_1 the focussing solenoid, and h'_1 , v_1 the yoke made of the horizontally deflecting coil h'_1 and the vertically deflecting coil v_1 (Figure 1); h'_1 and v_1 move the electron spot (over rectangle E_1) with constant velocities (v_h for horizontal scanning, and v_v for vertical scanning), while plates h_1 make the electron spot vibrate at the instantaneous frequency

$$\frac{\omega_1}{2\pi} = f_{11}$$

15 The focal length F of solenoid s_1 (having a winding of n turns, with a mean radius r centimeters, and through which flows an electric current of i amperes) is given by the formula:

$$F = 100 \frac{V_r}{n^2 i^2} \text{ centimeters}$$

20 V being the voltage accelerating the electrons, in volts. 30 c being the center of solenoid (s_1) and b the point where the yoke (h'_1 , v_1) is located, the electric current i must vary, as a function of time t , in such a manner that the electrons remain focussed on oil layer P_1 during all the scanning of the horizontal lines (aa') of E_1 , 35 in the direction of arrow f .

If ab is relatively large in comparison with aa' (Figure 3c), the angle between the perpendicular bb' on oil layer P_1 and the electron pencil may be considered as nearly constant and equal to φ_0 (φ_0 being the angle between bb' 40 and the straight line joining point b to a point of abscissa (referred to point a) $X_0 = \frac{3}{5} E$ for example (E being the width of rectangle E_1 , and θ the minimum angle between the electron pencil and oil layer P_1).

Let i_0 be the intensity of the electric current in the 45 winding of solenoid (s_1) corresponding to a perfect focusing of the electrons on P_1 when the electron spot is precisely at said point of abscissa X_0 , on scanning line aa' .

If current i varies as a function of time t in accordance with the following equation:

$$100 \frac{V_r}{n^2 i^2} = ca + y = ca + x \sin \varphi_0 = ca + (v_h \sin \varphi_0) \cdot t$$

or

$$55 i = \sqrt{\frac{100 V_r}{n^2 [ca + (v_h \sin \varphi_0) t]}}$$

only very small "aberrations" of the electronic image of the cross-over d_1 (on oil layer P_1) may occur during the scanning of rectangle E_1 .

This time variation of electric current i is automatically produced by means of "formation TF" shown at the right of Figure 3c: TF is a cathode ray tube having a rectilinear vertical cathode K, a Wenhelt cylinder W, a 60 pair of horizontally deflecting plates P, a slotted electrode SE, and a collecting electrode CE. Cylinder W controls the intensity of the flat electron beam produced by cathode K; plates P are energized by the relaxation oscillation generated by oscillator O_h (Figure 1), for the 65 horizontal scanning (at constant velocity v_h) of rectangle E_1 ; therefore the vertical electronic image of cathode K moves along the slot of electrode SE in synchronism with said horizontal scanning of E_1 .

70 The lines synchronizing pulses t_1 (received from the distant television transmitting station) are applied to

cathode K and cylinder W of tube TF, in order to cut off the electron beam during the rapidly decreasing part of the waveform of the relaxation oscillation produced by O_h (see, on Figure 3c, the lines representing, as functions of time t , said relaxation oscillation and said lines synchronizing pulses t_1). The slotted electrode SE (represented at the bottom of the right side of Figure 3c) is provided with a slot having a lower horizontal edge and an upper edge of a shape corresponding precisely to the above formula:

$$i = \sqrt{\frac{100V_r}{n^2[ca + (v_h \sin \varphi_0)t]}}$$

Therefore, at each instant, collecting electrode CE (which collects the electrons passing through the slot of SE) produces, across output resistor R, an electric voltage, which, after amplification through A, energizes focussing solenoid (sf_1) with the desired electric current i . Tube T and amplifier A constitute the device Th_1 of Figure 1; Th_2 is a similar arrangement associated with tube TC_2 . The minimum angle between the electron pencil and the oil layer P_1 of tube TC_1 (Figures 1 and 3c) is given by the formula:

$$\theta = \tan \frac{d}{E}$$

with $E=198$ millimeters and the maximum variation of the focal length F of focussing solenoid (sf_1) acting as a magnetic lens is:

$$\Delta F = E \cos \theta$$

In case of Figure 3b, $d=133$ mm., $\tan \theta = \frac{133}{198} = 0.67$, $\theta = 33.9$ degrees, $\cos \theta = 0.83$ and $\Delta F = 198 \times 0.83 = 164$ millimeters.

In case of Figure 3d, $d=163$ mm., $\tan \theta = \frac{163}{198} = 0.82$, $\theta = 39.4$ degrees. $\cos \theta = 0.77$ and $\Delta F = 198 \times 0.77 = 152$ millimeters.

In case of Figure 3f: (1) If $n_b = 16$, $n_v = 12.8$, $n_r = 9.14$, then $d = 108$ mm., $\tan \theta = \frac{108}{198} = 0.54$, $\theta = 28.4$ degrees, $\cos \theta = 0.88$ and $\Delta F = 198 \times 0.88 = 174$ millimeters.

(2) If $n_b = 8$, $n_v = 6.4$, $n_r = 4.57$, then $d = 217$ millimeters, $\tan \theta = \frac{217}{198} = 1.09$, $\theta = 47.4$ degrees, $\cos \theta = 0.676$ and $\Delta F = 198 \times 0.676 = 132.6$ millimeters.

If distance ba (Figure 3c), between the yoke and the oil layer along the shortest length of the electron pencil is of the order of 50 centimeters, the aberrations of the electron spot of the oil layer at both ends of a scanning line can be tolerated.

Referring again to Figure 1, plates h_2 are energized by a sine-wave $A_2 \sin \omega_2 t$ (generated by oscillator O_2) having a constant frequency

$$\left(\frac{\omega_2}{2\pi} \right)$$

and an amplitude modulated by modulator (md_2) under the control of a "weighted luminance signal" obtained at the output of electronic mixer (mxl), as explained hereafter, electric filter F_4 suppressing the carrier and one side-band; plates h_1 are energized by a sine-wave $C_3 = A_1 \sin \omega_1 t$ generated by oscillator O_1 and frequency modulated by modulator (md_1), as explained hereafter; this wave ($C_3 = A_1 \sin \omega_1 t$) controls the production of elemental diffracting gratings on the surface of oil layer P_1 , inside the various elemental squares of rectangle E_1 corresponding to the various colored "touches" superimposed by objective LO_1 on the detailed black and white drawing produced by objective LO_2 on projection screen EP.

The frequency

$$\left(f_1 = \frac{\omega_1}{2\pi} \right)$$

of wave $C_3 = A_1 \sin \omega_1 t$ varies (as a function of time t) by successive steps, under the control of a device

(described hereafter and shown on Figure 1, or on Figure 2f, or on Figure 2e, or on Figure 2g). Said frequency modulated wave ($A_1 \sin \omega_1 t$) is applied to the control grid g_1 of a gated amplifier (tetrode lb), the gating grid g_2 of which is energized by the output C_2 of "hue decoding cathode ray tube Td ." This tube Td is itself controlled by the output voltage C_1 of a phase detector DP (represented schematically on Figure 2c); to said phase detector DP are applied simultaneously, on one side, the amplified voltage of oscillator O (having same frequency and phase as the "color burst sr ," or as the oscillator generating the color subcarrier at the distant transmitting station), and, on the other side, through amplitude limiter (la), the received chrominance signal (chr) the phase of which characterizes the hue of the color to be reproduced; therefore the voltage C_1 , obtained at the output of phase detector DP, proportional to the cosine of the phase-shift between signals (chr) and (sr), characterizes also the color to be reproduced.

For the "step by step" modulation of the frequency f_1 of oscillator O_1 , any type of telegraphic frequency modulator may be used. For example the step-voltage "ech" (Fig. 1, having 3 successive values in each period) is applied to the conveniently biased grids of triodes, the outputs of which short-circuit (or insert) successively (without inertia) one or two parts of the inductance coil l (or of the capacitor c) of the anti-resonant circuit (lc) of an electronic tube having its grid and plate circuits coupled together, so that this tube oscillates with a frequency

$$\left(f_1 = \frac{1}{2\pi\sqrt{lc}} \right)$$

which varies step by step as a function of time; in this manner, it is possible to produce frequency deviations which are great by comparison with the basic frequency.

The number of lines n_1 (per millimeter) of an elemental diffracting grating R_1 produced on oil layer P_1 of cathode ray tube TC_1 by the electrons issued from cathode c_1 is a function of the "instantaneous frequency"

$$\left(f_{1i} = \frac{\omega_1}{2\pi} \right)$$

of the frequency modulated wave ($C_3 = A_1 \sin \omega_1 t$) applied to the plates h_1 which make horizontally vibrate the electron pencil produced by cathode c_1 . At each instant, this number of lines n_1 must be such that only the monochromatic radiations having wave lengths close to a value λ_1 (corresponding to the received chrominance signal (chr), and, therefore, to the hue of the color to be reproduced) can go through the transparent parts (e) of mask M in front of grating R_1 , in order to produce, on projection screen EP, a luminous spot having the desired color.

As an elemental diffracting grating is produced by an electron spot (on the oil layer) having a width of 0.02 millimeter and a length of 0.1 millimeter, it is possible to have a few elemental gratings in an elemental area (square of 1.5×1.5 millimeter) within rectangle E_1 of oil layer P_1 (Figure 1), which corresponds to the coarse colored picture to be produced on projection screen EP; various combinations of gratings (giving blue, or green, or red light, respectively) within the same elemental square of rectangle E_1 may be considered; two such combinations are described hereafter, in way of examples only, being understood that many other combinations could be realized within the frame of the present invention.

In the first case considered hereafter, six gratings (having each a height of 0.1 millimeter) are located inside said elemental square (height 1.5 millimeters) of rectangle E_1 of oil layer P_1 . Said rectangle E_1 is horizon-

tally scanned by the interlace process, each horizontal line being swept by the electrons during

$$\tau = \frac{1}{15,750} \text{ second}$$

in the American television standards. In the case of Figure 1 (N.T.S.C. color television system), there are 133 elemental squares in rectangle E_1 , and therefore each elemental square is swept during a time

$$t = \frac{\tau}{133} = \frac{1}{2.1 \cdot 10^6}$$

or approximately $\frac{1}{2}$ microsecond.

If, on three successive lines of the same field (lines $q, q+2, q+4$) are produced successively (within a given elemental square of E_1) a grating R_r giving red light, a grating R_v giving green light, and a grating R_b giving blue light, and if the same process is applied to lines $(q+1), (q+3)$ and $(q+5)$ of the following field, it is apparent that, on said six lines $(q \text{ to } q+5)$, the color to be reproduced (for the considered elemental area of the scene scanned at the transmitting station) will be obtained twice inside this elemental square of rectangle E_1 .

In the second case hereafter considered, (within a given elemental square of E_1), a grating R_r for red and a grating R_v for green are alternately produced on two successive lines of the same field (lines q and $q+2$, for example), whereas gratings R_b for blue are produced on all the lines of the field which follows (lines $(q+1), (q+3)$, etc.); a color filter absorbing slightly the blue luminous radiations can, in this case, be located in front of mirror M_1 of Figure 1; said color filter is not shown on Figure 1.

As an elemental square of rectangle E_1 is swept during a time

$$t = \frac{1}{15,750 \times 133} = \frac{1}{2.1 \cdot 10^6} \text{ second}$$

the instantaneous frequency f_{11} of the wave

$$(C_3 = A_1 \cdot \sin \omega_1 t)$$

applied to deflecting plates h_1 must have the following value, in order to produce a grating R_1 of n_1 lines per millimeter in the first and second cases mentioned above:

$$f_{11} = \frac{n_1}{t} = n_1 \cdot 2.1 \cdot 10^6 \text{ hertz}$$

The values of the instantaneous frequency f_{11} corresponding to the creation of blue, green or red lights on projection screen EP are therefore:

(1) In the case where:

$$\begin{aligned} n_b &= 8, n_v = 6.7 \text{ and } n_r = 4.57 \\ f_b &= 8 \times 2.1 = 16.8 \text{ megahertz} \\ f_v &= 6.4 \times 2.1 = 13.44 \text{ megahertz} \\ f_r &= 4.57 \times 2.1 = 9.59 \text{ megahertz} \end{aligned}$$

(2) In the case where:

$$\begin{aligned} n_b &= 16, n_v = 12.8 \text{ and } n_r = 9.14 \\ f_b &= 33.6 \text{ megahertz} \\ f_v &= 26.88 \text{ megahertz} \\ f_r &= 19.18 \text{ megahertz.} \end{aligned}$$

In an Eidophor projector, the voltage to be applied to the auxiliary deflecting plates (h_1 or h_2 on Figure 1) is of the order of 1 volt only; oscillators O_1 and O_2 (Figure 1) are therefore of the low power, high frequency type.

In the first case (considered hereabove), the frequency f_1 of oscillator O_1 must have the instantaneous value f_r during

$$\tau = \frac{1}{15,750} \text{ second}$$

(duration of one scanning line in the American television standards), then, the value f_v during the following period

τ , then the value f_b during the next period τ , and so on. For achieving that, use can be made of generator GR (Figure 1) producing square waves having a period equal to 3τ (said generator GR being synchronized by the received line synchronizing pulses t_1 at scanning lines frequency).

CD is a "differentiating circuit" (the word "differentiating" having its mathematical meaning), producing a positive "pip" for the initial rise of each pulse, and a negative "pip" for the final transient part of said pulse. These "pips" trigger two multivibrators (MV, MV') producing two similar square-wave outputs, 180 degrees out of phase, one pulse (of each cycle) having a duration 2τ , whereas the pulse of the other has a duration of τ . After passing through a clipper in each channel (dc, dc'), these two pulse signals are mixed in electronic mixer MX, to achieve a 3 step-voltage wave-form with a step duration of τ . After amplification by amplifier AM, the desired 3 step-voltage "ech" (having three successive values in each period 3τ) is obtained, said values corresponding to the ratios between the desired instantaneous frequencies for the wave $C_3 = A_1 \cdot \sin \omega_1 t$, that is to say: f_r, f_v, f_b .

This 3 step-voltage (ech) modulates the frequency

$$\left(f_1 = \frac{\omega_1}{2\pi} \right)$$

of the sine-wave generated by oscillator O_1 , by means of the frequency modulator (mdl) of telegraphic type.

The frequency modulated wave ($C_3 = A_1 \cdot \sin \omega_1 t$) is applied to the control grid g_1 of gated amplifier lb , the gating grid g_2 of which is controlled by the output of hue decoding tube Td , and is negatively biased by battery B.

Decoding tube Td (Figure 1) has a small cathode K, horizontally deflecting plates H (energized by phase detector DP), vertically deflecting plates V (energized by the 3-step voltage "ech" of period 3τ), a decoding electrode ED (represented on Figure 2d, and having 3 slits R, V, B), and a collecting electrode EC behind said slits. At each instant, the electronic image of cathode K is (under the control of 3 step-voltage "ech") located at the level of one of said 3 slits of decoding electrode ED, at a point determined by the voltage C_1 (produced at the output of phase detector DP and applied to deflecting plates H). Said electronic image is, in case of Figure 1, on slit R (corresponding to red primary color) during a time τ , then, on slit V (corresponding to green primary color) during the following period τ , then, on slit B (corresponding to blue primary color) during the following period τ , and so on, under the control of 3 step-voltage "ech" applied to plates V of tube Td .

The voltage $C_1 = 2E_1 \cdot \cos(\alpha - \beta)$, as explained hereafter, characterizes the hue of the color to be reproduced, and is therefore called hereafter "hue signal"; acting on plates H of tube Td , said hue signal positions, at each instant, the electronic image of cathode K on a particular vertical line of decoding electrode ED cutting one, or two, or three slits (R red, V green, B blue) if one, or two, or three primary colors are necessary for the reproduction of the color on the corresponding part of projection screen EP.

If, at a given instant, the electronic image of cathode K is on a solid part of decoding electrode ED, no electron can reach collecting electrode EC, and the output voltage C_2 of tube Td is unable to equalize (or exceed) the bias B of gating grid g_2 of tetrode lb ; therefore the signal $C_3 = A_1 \cdot \sin \omega_1 t$ is no longer applied to plates h_1 of tube TC_1 ; a uniform distribution of electrons takes place on oil layer P_1 because only the linear part of the sawtooth wave of oscillator Oh (acting on coil h'_1) moves the electron pencil of tube TC_1 ; the oil layer P_1 has no deformation (no grating) at this place; no light is produced by tube TC_1 on the corresponding point of projection screen EP.

If, on the contrary, at a given instant, the electronic image of cathode K is, for example, on a point of slit V of electrode ED, collecting electrode EC receives electrons, and (at the output of tube T_d) a signal C_2 is produced with an intensity exceeding the voltage of battery B biasing gating electrode g_2 of tube lb ; the frequency modulated wave ($C_3 = A_1 \cdot \sin \omega_1 t$) applied to control grid g_1 of lb is amplified, and reaches plates h_1 of tube TC_1 ; precisely, at this instant, the instantaneous frequency

$$(f_{1i} = \frac{\omega_1}{2\pi})$$

of C_3 has the value f_v necessary for producing, on oil layer P_1 in tube TC_1 , an elemental diffracting grating R_v having n_v lines per millimeter and giving green light (through mask M and objective lens LO_1) on the appropriate point of projection screen EP, because rectangles E_1 and E_2 of oil layers P_1 and P_2 (Figure 1) are homothetic, and are scanned in perfect synchronism, with the same relaxation oscillators O_h and O_v .

Instead of the frequency modulator mdl shown at the bottom of the left of Figure 1, use can be made of the device shown on the appended Figure 2f. G_b , G_v , G_r represent oscillators generating for example sine-waves having respectively the frequencies f_b , f_v , f_r proportional to the numbers (n_b , n_v , n_r) of lines per millimeter of the elemental diffracting grating R_b , R_v , R_r ; these waves are applied respectively to the control grids (g_b , g_v , g_r) of amplifiers a_b , a_v , a_r , the gating grids of which are g'_b , g'_v , g'_r . D is the arrangement of Figure 1 generating a three-step voltage (ech) having a period 3τ (τ being the duration of one scanning line); D is synchronized by the lines synchronizing pulses t_1 coming from the distant television transmitting station.

(com) is a 3 contact beam switching tube; for example, as shown on Figure 2f, (com) is a cathode ray tube having a cathode c , vertically deflecting plates V , an electrode E provided with 3 holes above each other and behind which are located three collecting electrodes e_1 , e_2 , e_3 connected respectively to three output resistors r_1 , r_2 , r_3 . The voltages produced across said resistors are applied to the gating grids g'_b , g'_v , g'_r of amplifiers a_b , a_v , a_r respectively. T_d is the hue decoding tube of Figure 1, and lb is its associated tetrode acting as gated amplifier, with a control grid g_1 and a gating grid g_2 , negatively biased by battery B and controlled by signal C_2 produced by tube T_d . The vertically deflecting plates V of tube (com) and V of tube T_d are both energized by said 3 step voltage (ech). The plates of amplifiers a_b , a_v , a_r are connected to electronic mixer M which feeds the control grid g_1 of tetrode lb .

When the electronic image of cathode c of tube (com) is successively in front of collecting electrodes e_1 , e_2 , e_3 (during three successive scanning lines of duration τ), the electronic image of cathode K of tube T_d is precisely at the level of slits R (red), V (green) and B (blue) of decoding electrode ED of tube T_d , successively; and, precisely, at the same instants, the voltages across resistors r_1 , r_2 , r_3 (acting on gating grids g'_b , g'_v , g'_r of amplifiers a_b , a_v , a_r) unblock successively said amplifiers; therefore control grid g_1 of tetrode lb receives successively the frequency modulated sine wave $C_3 = A_1 \cdot \sin \omega_1 t$ (to be applied to deflecting plates h_1 of tube TC_1 , Figure 1) with the successive instantaneous frequencies (f_r , f_v , f_b) which are necessary for creating the elemental diffracting gratings R_r , R_v , R_b on rectangle E_1 of oil layer P_1 of said tube TC_1 .

In the second case considered above, the instantaneous frequency f_{1i} of wave $A_1 \cdot \sin \omega_1 t$ must have the value f_r during a period

$$\tau = \frac{1}{15,750} \text{ second}$$

then the value f_v during the following period τ , and so

on during two successive lines of the first field; during all the second field (in interlace scanning), the frequency f_{1i} must keep the same value f_b .

In this case, instead of the device represented at the bottom (on the left) of Figure 1, for generating the frequency modulated wave $C_3 = A_1 \cdot \sin \omega_1 t$, use is made of the device shown on Figure 2e. O'_1 is an oscillator generating a wave of constant frequency f_b . O_1 is an oscillator generating a wave of frequency f_{1i} having the value f_r during a period τ , when all its inductance coil l (or all its capacitor c) is inserted in the anti-resonant circuit, and having the value f_v during the following period τ when an appropriate part of said inductance coil l (or of said capacitor c) is short-circuited, the frequency (f_{1i}) being

$$f_{1i} = \frac{1}{2\pi\sqrt{lc}}$$

The electronic device md (Figure 2e), synchronized by the received line synchronizing pulses t_1 , operates

$$(\text{every } 2\tau \text{ second} = \frac{2}{15,750} \text{ second})$$

this short-circuiting of part of coil l (or part of capacitor c); the electronic switch ($basc$), synchronized by the received field synchronizing signals t_1 , connects alternately, in two successive fields, oscillator O_1 and oscillator O'_1 to the control grid g_1 of gated amplifier lb of Figure 1.

At the same time, the vertically deflecting plates V of tube T_d (Figure 1) are energized by the device shown on Figure 2e: GR' is a generator of a square-wave of period 2τ (one pulse τ wide, every period), synchronized by the received lines synchronizing pulses t_1 , and bringing the electronic image of cathode K of tube T_d successively at the level of slit R and at the level of slit V of decoding electrode ED of tube T_d during two successive scanning lines of one field, when electronic switch ($basc'$) is on its left hand side contact; during all the following field, electronic switch ($basc'$)—synchronized by the received field synchronizing signals t_1 —is on its right hand contact and connects plates V to a battery P producing (across plates V) a voltage bringing the electronic image of said cathode K at the level of slit B of said electrode ED.

Instead of the device shown on Figure 2e, use can be made of the device shown on Figure 2g. τ being the duration of one scanning line and T the duration of one field, use is then made of two multivibrators: ($mv1$), producing one square pulse τ wide every 2τ seconds, and ($mv2$), producing one square pulse T wide every $2T$ seconds. These two multivibrators are respectively synchronized by the received lines synchronizing pulses t_1 and by the received field synchronizing signals t_1 .

($mv1$) controls directly the gating grid g'_r of amplifier a_r fed by G_r , which generates a sine-wave of frequency f_r ; ($mv1$) controls indirectly (through inverting triode i_1) the gating grid g'_v of amplifier a_v fed by G_v , which generates a sine-wave of frequency f_v . The output voltages of amplifiers a_r and a_v are applied to electronic mixer m_1 .

($mv2$) controls directly the gating grid g'_1 of amplifier a_1 which is fed by electronic mixer m_1 ; ($mv2$) controls indirectly (through inverting triode i'_1) the gating grid g'_b of amplifier a_b , which is fed by G_b generating a sine-wave of frequency f_b . The output voltages of amplifiers a_1 and a_b are applied to electronic mixer m_2 , which energizes the control grid g_1 of tetrode lb , whereas the gating grid g_2 of said tetrode lb is negatively biased by battery B and is also submitted to the control of signal C_2 produced at the output of hue decoding tube T_d .

The horizontally deflecting plates H of T_d are energized by hue signal C_1 , whereas the vertically deflecting plates V are energized by electronic mixer m_3 to the input of which are applied: (1) through amplifier a_2 the wave produced by

(mvI), and (2) through amplifier a_3 a positive D.C. voltage due to battery P. The gating grid g'_2 of amplifier a_2 is directly controlled by (mvI), and the gating grid g'_3 of amplifier a_3 is indirectly controlled (through inverting triode i'_2) by (mvI). During the field when a_2 is unblocked, plates V of tube Td position the electronic image of cathode K successively at the level of slit R and at the level of slit V of ED during two successive scanning lines; during the following field, a_3 is unblocked and said electronic image of K is positioned at the level of slit B of ED.

Several modifications may be done in the electronic devices (described hereabove) for producing a wave of varying periodicity in order to create elemental diffracting gratings on oil layer P_1 of tube TC_1 (Figure 1). For example, instead of applying to horizontally deflecting plates h_1 of tube TC a sine-wave of variable frequency ($A_1 \sin \omega_1 t$), use can be made of periodic wave-shapes other than a sinusoid; for example, oscillators O_1 and O'_1 (Figure 2e), or devices G_b , G_v , G_r (Figure 2f or Figure 2g) can generate saw-tooth waves, or rectangular waves, having appropriate fundamental frequencies; if a rectangular wave-form is used, the ratio between the duration of the rectangular pulse and the time interval between 2 consecutive pulses should have an appropriate value.

As the intensity (but not the positions) of the diffraction spectra depends on the ratio between the width of a line and the distance between two consecutive lines of the diffracting grating, it is possible to use, as generators G_b , G_v , G_r of periodic waves of respective periodicities f_b , f_v , f_r (Figure 2f, or Figure 2g), devices generating periodical rectangular waves, having (in each period) a pulse, the duration of which is function of the low-frequency part l' of the received luminance signal, but only when the elemental area of the scene (being scanned at the transmitting station) to be reproduced on the projection screen at the receiving station has a uniform, very saturated color, with brightness variations from one point to the other.

Such a device comprises: (1) a multivibrator MV generating a rectangular wave of desired periodicity, (2) a modulator MA, for modulating the amplitude of the rectangular pulse within the successive periods, (3) a converter (CAD) for changing the pulse-amplitude-modulation into a pulse-duration-modulation, and (4) an amplifier A_m , to the control grid of which is applied said low-frequency part l' of the luminance spectrum, whereas its gating grid is negatively biased by a battery, and is also submitted to the action of saturation signal S (which is proportional to the degree of saturation of the color to be reproduced).

The output voltages of amplifier A_m and of multivibrator MV are applied to amplitude modulator MA; but A_m is blocked except when a very saturated color must be reproduced, so that saturation signal S then exceeds the value of the negative bias of the gating grid.

Only in such a case, amplifier A_m is active, and applies (with the desired amplitudes) the low-frequency part l' of the received luminance signal to amplitude-modulator MA, for modulating the amplitudes of the successive rectangular pulses generated by multivibrator MV; converter CAD changes said pulse-amplitude-modulation into pulse-duration-modulation; so is obtained, at the output of converter CAD, a periodical wave having the desired periodicity (f_b , f_v or f_r), and having (in each period) a pulse, the duration of which is a function of the luminance to be reproduced; this periodical wave provides, on oil layer P_1 of tube TC_1 (Figure 1), successive diffracting gratings having all the same number of lines per millimeter, but different ratios between the width of a line and the distance between 2 successive lines; said gratings produce successive diffraction spectra having different luminous intensities, in accordance with the time variations of the received luminance energy. Therefore, on

projection screen EP (Figure 1), colored touches of the same very saturated color, but of different brightness are successively produced.

The two Eidophor projectors TC_1 and TC_2 of Figure 1 cooperate as follows under the control of the received composite video-signal V restored, at the receiving station, after the video-detector DV. SVS is the synchrono-video-separator (amplitude filter), which separates the line synchronizing pulses t_1 (controlling the sawtooth wave generator Oh), the field synchronizing signals t_2 (controlling the sawtooth wave generator Ov), and the video-signal carrying the luminance and chrominance informations and having the spectrum represented on Figure 2a, in case of the N.T.S.C. color television system; after amplification by amplifier A_1 (band width B_1 , Figure 2a), the video-signal spectrum is divided by electronic frequency filters in the following manner:

Filter F_2 (bandwidth B_2 , Figure 2a) separates the part l'' of the luminance concerning the principal details of the drawing of the scene being scanned at the distant transmitting station;

Filter F'_2 (bandwidth B'_2 , Figure 2a) separates the chrominance (chr), (modulated color subcarrier), with negligible components of luminance;

Filter F_3 (bandwidth B_3 , equal to B'_2 , Figure 2a) separates the part l' of the luminance containing the greatest part of the luminance energy.

A_{sr} is an amplifier having a very narrow frequency band (centered on the color subcarrier frequency), and having a gating grid g_1 controlled by the received line synchronizing pulses t_1 ; A_{sr} separates (at the beginning of each scanning line) the "color burst sr " (color reference signal) made of a few periods of the unmodulated color subcarrier.

O is a local oscillator generating a sine-wave at the color subcarrier frequency; the phase and frequency of said wave are maintained in perfect synchronism with the oscillator generating the color subcarrier at the transmitting station in the following classical manner: the wave produced by O and the received color burst sr are simultaneously applied to phase detector dp , the output of which (through circuit ct , of appropriate time constant) controls the bias of a reactance tube associated with oscillator O , so that any accidental phase-shift between

local oscillator O and the unmodulated color subcarrier of the transmitting station is automatically corrected.

The difference of phase between the color burst sr (or the so corrected local oscillator O) on one side, and the received chrominance signal (chr) obtained at the output of filter F'_2 on the other side is, in the N.T.S.C. system, a function of the dominant wave length or hue of the color to be reproduced, in accordance with the circular diagram of Figure 2b, on which the following table is based:

Color to be reproduced	Difference of phase ($\alpha - \beta$) between the chrominance signal (chr) and the color burst (sr); relative values in degrees	Dominant wavelength μ_1 (hue) of the color to be reproduced, expressed in microns $\times 10^{-3}$
red	0	700.
purple	103 - 61 = 42	complementary to 510.
blue	180 - (347 - 283) = 116	420.
bluish green	180	495.
green	180 + 42 = 222	510.
yellow	180 + 116 = 296	575.

Referring to Figures 1 and 2c, phase detector DP receives simultaneously: through amplifier a , the wave of local oscillator O , and through amplitude limiter la , the chrominance signal (chr) coming from filter F'_2 ; these two waves, called respectively E_2/β and E_1/α on Figure 2c, are applied (through transformers tr_2 and tr_1) to the plates of diodes V_1 , V_2 , the amplitude E_2

being much larger than amplitude E_1 because of the action of amplifier a , and E_1 being practically constant because of the action of amplitude limiter la . At the output of phase detector DP (Figures 2c and 1), a wave $C_1=2E_1\cos(\alpha-\beta)$ is obtained: it is the "hue signal" characterizing the hue of the color to be reproduced, and applied to the horizontally deflecting plates H of hue decoding cathode ray tube Td .

In case of a purely black (or purely white) part of the scene being scanned at the transmitting station, the color subcarrier is no more modulated at said station and reaches the receiving station with the same phase as the color burst sr . Therefore the "hue signal" [$C_1=2E_1\cos(\alpha-\beta)$] is zero, and plates H position the electronic image of cathode K of tube Td on the solid part (on the left) of decoding electrode ED (Figure 1 and Figure 2d). Then signal C_2 , at the output of tube Td , is unable to overcome the bias B of the gating grid g_2 of tube lb , and no signal ($C_3=A_1\sin\omega_1t$) reaches the auxiliary deflecting plates h_1 of Eidophor projector TC_1 ; no deformation is produced in rectangle E_1 of oil layer P_1 , and no colored light is thrown by projector TC_1 on projection screen EP , on which remains only the black and white drawing of the scene being scanned at the transmitting station.

Referring again to Figure 1, the part l' (band B_3) of the luminance spectrum is, at the output of filter F_3 , applied to the control grid of pentode L acting as "luminance weighting device"; after amplitude detector DA , the amplitude of the received chrominance signal chr (color subcarrier, amplitude modulated by the degree of saturation of the color at the transmitting station) constitutes the "saturation signal S " proportional to the degree of saturation of the color to be reproduced at the receiving station; said saturation signal S provides (through rheostat r, r'), to the control grid of pentode L , a bias such that the gain of said pentode varies in inverse proportionality to the degree of saturation of the color to be reproduced on projection screen EP . Consequently the voltage l'_1 at the output of pentode L is greater, the smaller S (or said degree of saturation) is.

Electronic mixer (mxl) mixes said output voltage l'_1 with part l'' of the luminance spectrum (band B_2 , Figure 2a) carrying the details of the drawing of the scene being scanned at the transmitting station. The "weighted luminance signal" so obtained at the output of mixer (mxl) modulates the amplitude of the wave ($A_2\sin\omega_2t$) generated by oscillator O_2 , through amplitude modulator (md_2). After filter F_4 (which suppresses the carrier and one side-band), the single side-band-amplitude-modulated wave ($A_2\sin\omega_2t$) energizes plates h_2 of Eidophor projector TC_2 , which, in the classical manner, provides, after reflection on mirror M_2 , the desired black and white drawing on screen EP ; the right proportions between the white light produced by TC_2 and the colored light produced by TC_1 are secured by the appropriate adjustment of rheostat r, r' .

As mask M (Figure 1) associated with projector TC_1 cuts off the central white image I_1 of source S_1 , but only $\frac{2}{3}$ of the spectra (s_1 and s_1') on both sides of said image I_1 (see Figure 3a), there remains a small amount of white light in the colored touches brought by TC_1 onto screen EP ; account of this fact is taken when adjusting the rheostat r, r' which provides the bias of the control grid of pentode L . Said rheostat r, r' must be adjusted also in such a manner that electric voltage l'_1 (at the output of pentode L) be zero when saturation signal S is maximum, because the color to be reproduced then is very saturated.

When a relatively large part of the scene being scanned at the distant transmitting station has a uniformly very saturated color, part l'' of the luminance spectrum (band B_2 , Figure 2a) still acts (through mixer mxl , oscillator O_2 and amplitude modulator md_2) on plates h_2 of projector TC_2 (although l'_1 is then equal to zero); while

the brightness of the colored touch produced by projector TC_1 remains constant (if the amplitude A_1 of the frequency modulated wave ($C_3=A_1\sin\omega_1t$) applied to plates h_1 remains constant), part l'' of the luminance spectrum produces "saturation variations" which give the illusion of "brightness variations" for the small details of said part of said scene.

Figure 1c illustrates the case when it is possible to have a large transparent plate PL with an oil layer P inside one single Eidophor projector TC (replacing the tubes TC_1 and TC_2 of Figure 1): two pencils of electrons scan respectively, in perfect synchronism, the homothetic rectangles E_1, E_2 on the surface of said oil layer P , plate PL rotating slowly in the direction of arrow f within tube TC . R is a small oil container below tube TC , although it is shown, on Figure 1c, as a transversal cut brought in the plane of plate PL . The oil is delivered under pressure to plate PL (from container R , through pipes p_1, p_2 and oil filters F_1, F_2) by means of "delivering bars ba_1, ba_2 " having slots close to the surface of PL , and lying in a radial direction. As the plate PL rotates, the oil is transported to similarly arranged "smoothing bars be_1, be_2 " whose distance to plate PL is such that the thickness of the oil layer is of the order of 0.1 millimeter in the useful parts, where rectangles E_1, E_2 are bombarded by electrons.

"Protecting bars bp_1, bp_2 " protect said useful parts against any disturbance due to the liquid delivered in a direction opposite to arrow f (which is the direction of rotation of PL).

On the other side of said protecting bars, said liquid delivered in a direction opposite to arrow f pushes away the oil already bombarded, and hence partially polymerised by the electron beams. The protective bars (bp_1, bp_2) are maintained at a low temperature in order to cool said already bombarded oil, which then (together with the newly delivered excess oil) flows into container R , under plate PL .

P_0 is a recirculating pump (inside container R); the viscous oil enters the chamber where the slowly moving smooth rotor of P_0 transports it along a narrow slit to a barrier (nearly touching the rotor); the oil is so forced under pressure into delivering bars ba_1, ba_2 —and any undesirable disturbance of the oil surface is so avoided.

Figure 1d illustrates the operation of delivering bar ba_1 , smoothing bar be_1 , protecting bar bp_1 , and also the evacuation of the already bombarded oil towards container R , under plate PL , which rotates in the direction of arrow f ; the oil is represented by small dots on said Figure 1b. The numerical values quoted in the above description must be considered only as orders of magnitude.

The above description concerns the application of the invention to the American N.T.S.C. color television system; but this invention can be applied, just as well, to any compatible color television system based on any kind of coding of the luminance and the chrominance.

Figure 4 (for example) shows the color triangle divided in sectors corresponding to the various chromaticities that the human eye can easily discriminate from each other; on said triangle (so divided) is based a color television system in which the color subcarrier is modulated only in amplitude by a "chrominance signal," which is a voltage proportional to the number of the sector representing the chromaticity to be reproduced at the receiving station; this "chrominance signal" therefore carries informations concerning both the hue and the degree of saturation of said chromaticity to be reproduced. In this case, the phase detector DP of Figure 1 is not used any more, and the amplitude detector DA (Figure 4a) feeds directly the horizontally deflecting plates H, H' of two decoding cathode ray tubes Td, Td' , decoding respectively the saturation signal S , and the hue signal C_2 corresponding to the desired chromaticity.

The saturation decoding cathode ray tube Td' contains

a vertical rectilinear cathode and a decoding electrode ED' provided with a slit having one rectilinear edge and one sinuous edge, because signal C_1 (produced by amplitude detector DA energized by the received modulated color subcarrier at the output of filter F'_2), applied to plates H' , is proportional to the various numbers of the sectors of the triangle of Figure 4, whereas the degrees of saturation (of the chromaticities represented respectively by said sectors) vary alternately from a low value (for a central sector) to a high value (for a peripheric sector) when the increasing order of sector numbers is followed. The hue decoding cathode ray tube T_d (Figure 4a) operates like the same tube T_d on Figure 1.

Without further analysis, the foregoing will so fully reveal the gist of the present invention that others can, by applying current knowledge, readily adapt it for various applications without omitting features that, from the stand-point of prior art, fairly constitute essential characteristics of the generic or specific aspects of this invention, and, therefore, such adaptations should, and are intended to be comprehended within the meaning and range of equivalence of the following claims.

What is claimed as new and desired to be secured by Letters Patent is:

1. Color television receiving station of the type in which the received luminance signal controls the production (on a projection screen) of a detailed black and white drawing of the scene being scanned at the distant transmitting station, while the received chrominance signal controls the production of a relatively coarse colored picture of said scene superimposed on said black and white drawing, comprising in combination: means for separating from each other said received luminance signal, said received chrominance signal, the color reference signal or "color burst" received at the beginning of each scanning line, the received lines synchronizing pulses, and the received fields synchronizing signals, means for extracting (from said chrominance signal) a so-called "hue signal" characterizing the hue of the color to be reproduced, and a so-called "saturation signal" proportional to the degree of saturation of said color to be reproduced, a luminance weighting device controlled by said received luminance signal and by said saturation signal, for producing a so-called "weighted luminance signal," a first oscillator, an electronic amplitude modulator associated with said first oscillator for producing a wave of constant frequency, whose amplitude is modulated by said weighted luminance signal, a device generating a wave of varying periodicity, a gated amplifier having its control grid energized by said wave of varying periodicity and its gating grid negatively biased, said hue signal being applied to said gating grid for unblocking said amplifier when said hue signal overcomes said negative bias, two cathode ray tubes having each a transparent rotating plate with an oil layer, the face of said plate in contact with the oil being electro-conductive and raised to a high positive potential referred to the cathode, two relaxation oscillators respectively controlled by said receiving lines synchronizing pulses and by said received fields synchronizing signals, deflecting coils acting on the electron pencils of said tubes and energized by the saw-tooth waves generated respectively by said relaxation oscillators, whereby two homothetic rectangles of the oil layers of said tubes are scanned, in perfect synchronism, horizontally and vertically with constant velocities, power sources of white light illuminating, at normal incidence, through said rotating transparent plates, said homothetic rectangles of said oil layers, deflecting plates energized by said wave having its amplitude modulated by said weighted luminance signal, for producing a vibration of constant frequency superimposed on said constant velocity horizontal sweeping, whereby deformations are produced on the surface of the oil layer of the first of said cathode ray tubes, two optically conjugated bar systems through which can pass only the white light diffracted by the deformations of said oil

layer, a first objective imaging said deformations of said oil layer onto said projection screen, for producing said detailed black and white drawing of the scene scanned at the distant transmitting station, deflecting plates energized by said wave of varying periodicity, for producing a vibration of variable periodicity superimposed on said constant velocity horizontal sweeping, whereby deformations are produced on the surface of the oil layer of the second of said cathode ray tubes, a mask made of opaque parts separated by transparent parts through which can pass only the desired colored light diffracted by the deformations of said oil layer, a second objective imaging said deformations of said oil layer onto said projection screen for adding colored touches to said detailed drawing, whereby said scene, being scanned at the distant transmitting station, is reproduced in colors on said projection screen.

2. Color television receiving station in accordance with claim 1 in which a network of elemental lenses is associated with said mask, said elemental lenses corresponding to the various elemental squares of the rectangle of the oil layer being scanned by said electron pencil which vibrates under the control of said wave of varying periodicity.

25 3. Color television receiving station in accordance with claim 2, in which said mask is located on the plane containing the focal points of all said elemental lenses.

4. Color television receiving station in accordance with claim 2 comprising: a network of elemental lenses corresponding to the various elemental squares of said rectangle of oil layer scanned by said electron pencil which vibrates under the control of said wave of varying periodicity, a mask made of opaque parts separated by transparent parts, and located immediately below said network of elemental lenses, a bar system for making perfectly parallel the rays of white light illuminating said rectangle of oil layer, and a screen provided with small holes, and located in the plane containing the focal points of said elemental lenses, for suppressing any light except the desired colored lights.

5. Color television receiving station in accordance with claim 1 comprising: a bar system through which pass the white luminous rays illuminating said rectangle of the oil layer scanned by said electron pencil which vibrates under the control of said wave of varying periodicity, and a mask, located on the other side of said oil layer, and having opaque parts exactly above the slits of said bar system, said opaque parts being separated by transparent parts through which pass only the desired colored lights.

6. Color television receiving station in accordance with claim 1 in which said device generating said wave of varying periodicity comprises: an oscillator generating a sine-wave, a frequency modulator of telegraphic type acting on the anti-resonant circuit of said oscillator, and a 3-step voltage generator controlling said frequency modulator and synchronized by said received lines synchronizing pulses.

7. Color television receiving station in accordance with claim 1 in which said device generating said wave of varying periodicity comprises: a first oscillator generating a sine-wave, a frequency modulator of telegraphic type synchronised by the received lines synchronizing pulses and acting upon the anti-resonant circuit of said first oscillator, a second oscillator generating another sine-wave, and an electronic switch, synchronized by the received fields synchronizing signals, for substituting said second oscillator to said first oscillator every two fields.

8. Color television receiving station in accordance with claim 1 in which said device generating said wave of varying periodicity comprises: three oscillators generating three sine-waves of fixed frequencies, three gated amplifiers fed by said oscillators, an electronic switch opening successively the gates of said amplifiers, and a device, synchronized by the received lines synchronizing

pulses, generating a 3-step voltage controlling said electronic switch.

9. Color television receiving station in accordance with claim 1 in which said device generating said wave of varying periodicity comprises: three oscillators generating three sine-waves of fixed frequencies, gated amplifiers and electronic mixers associated with said oscillators, and two multivibrators acting on the gating grids of said amplifiers, and respectively synchronized by the received lines synchronizing pulses and the received fields synchronizing signals.

10. Color television receiving station in accordance with claim 1, in which the voltage of varying periodicity, applied to the auxiliary horizontally deflecting plates acting on the electron pencil of the tube producing colored touches on said projection screen, has a saw-tooth waveform, having a period corresponding successively to the numbers of lines (per millimeter) of the elemental diffracting gratings to be produced on the oil layer of said tube.

11. Color television receiving station in accordance with claim 1, in which the voltage of varying periodicity, applied to the auxiliary horizontally deflecting plates acting on the electron pencil of the tube producing colored touches on said projection screen, has a rectangular waveform of appropriate ratio (between the duration of the rectangular pulse and the time interval between two consecutive pulses), and has a fundamental period corresponding successively to the numbers of lines (per millimeter) of the elemental diffracting gratings to be produced on the oil layer of said tube..

12. Color television receiving station in accordance with claim 11, in which the devices acting on the electron pencil of the tube producing colored touches on said projection screen comprise: a multivibrator generating a rectangular wave of a periodicity corresponding to a primary component of the hue of the color to be reproduced, a modulator for modulating the amplitude of the rectangular pulse within the successive periods of said wave, a converter of pulse-amplitude-modulation into pulse-duration-modulation, and a gated amplifier, the control grid of which is energized by the low-frequency part of said received luminance signal, whereas the gating grid is negatively biased by a battery, and is also submitted to the action of said saturation signal proportional to the degree of saturation of said color to be reproduced, the output voltages of said amplifier and of said multivibrator being applied to said amplitude modulator,

whereby, at the output of said converter, but only during the reproduction of very saturated colors, is obtained a periodical wave having a periodicity corresponding to said primary component of color to be reproduced, but having, in each period, a pulse of a duration function of the luminance to be reproduced.

13. Color television receiving station in accordance with claim 1, in which a single cathode ray tube with two electron guns replaces the two tubes recited in claim 1, said single tube comprising: a rotating transparent plate with an oil layer, two homothetic rectangles of which are scanned, in perfect synchronism, by the electron pencils issued from said electron guns, an oil container located under said transparent plate, a rotating pump inside said container, two delivering bars fed in oil by said pump, for delivering oil to said transparent plate, two smoothing bars, for giving a small uniform thickness to the useful parts of said oil layer where said homothetic rectangles are located, two protecting bars, for protecting said useful parts against any disturbance due to the oil delivered in a direction opposite to the rotation of said transparent plate, and a device for maintaining said protecting bars at a low temperature, in order to cool the oil already bombarded by said electron pencils.

14. Color television receiving station in accordance with claim 1, in which the devices for focusing the electrons (of the electron pencils of said tubes producing on said projection screen the pictures of the scene being scanned at the transmitting station) upon the oil layers of said tubes, comprise: a solenoid acting as a magnetic lens on said electrons, a cathode ray tube provided with a rectilinear vertical cathode, a Wenhelt cylinder, a slotted electrode, a collecting electrode behind said slotted electrode, and a pair of horizontally deflecting plates, energized by said relaxation oscillator which produces the constant velocity horizontal scanning of said oil layers, and an amplifier, energized by the output voltage of said cathode ray tube, for feeding the winding of said solenoid, said received lines synchronizing pulses being applied to said cathode and to said Wenhelt cylinder of said cathode ray tube.
